UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

ELECTRICAL STARTING APPARATUS.

1,349,870.

Application filed November 21, 1914. Serial No. 873,264.

Specification of Letters Patent. Patented Aug. 17, 1920.

To all whom it may concern:

Be it known that I, JOSEPH BIJUR, a citizen of the United States, and residing at New York, in the county of New York and State of New York, have invented a new and Improved Electrical Starting Apparatus; of which the following specification is a full disclosure.

This invention relates to dynamo-electric machinery and more particularly to such machinery as used in connection with the starting of internal combustion engines.

One of the objects thereof is to provide practical, inexpensive and positively acting apparatus of the above nature in which certain desired characteristics are given to the action of the dynamo.

Other objects will be in part obvious from the annexed drawings and in part indicated in connection therewith by the following analysis of this invention.

This invention accordingly consists in the features of construction, combinations of parts, and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a sectional elevation of a dynamo with related parts.

Fig. 2 is a diagrammatic plan of electrical connections.

Fig. 3 is an end view of a switch member.

Referring now to Fig. 1 of the drawings, there is diagrammatically shown at 1 the fly wheel of an internal combustion engine 2, this wheel being provided with a gear 3. Mounted adjacent the fly wheel is a dynamo, preferably an electric motor, the armature shaft 4 of which is provided with a pinion 5, adapted upon being moved endwise, as hereinafter described, to come into mesh with gear 3. It may here be noted that terms of the nature of "gear" are used in a broad sense to indicate any power trans-

mitting connection whether of the frictional or positive type.

The armature 6 of the dynamo is normally out of registry with the field magnet 7 and is provided with an elongated commutator 8 adapted to slide in operative relation to the brushes as the armature moves endwise.

The construction and action of the parts above described are substantially identical with similar parts in my co-pending application, Serial No. 872,702, filed November 18th 1914, issued July 1st, 1919 as Patent No. 1,308,158, to which reference is here made.

The commutator end of the shaft 4 is bored out as indicated at 9 to receive a spring 10 which abuts against a post 11 in the dynamo head 12 and tends to throw the armature into the normal position shown. Shaft 4 slides within a guide 13 and during its movement abuts against a collar 14 and forces it into operative relation to the electromagnet 15 in opposition to the force of spring 16 by an action substantially similar to that set forth in my co-pending application above referred to.

Secured to collar 14 as by the arms 17 insulated therefrom, is a switch member best shown in Fig. 3 of the drawings. This member comprises a connecting bar 18 at each end of which is a curved contact portion 19 adapted to coact with a mating contact member 20 in embracing the stationary contact posts hereinafter described. Members 19 and 20 are preferably urged toward one another by connecting pins 21 and springs 22.

Mounted upon an inner head of the dynamo casing 23 and insulated therefrom at 24 is a contact post 25 presenting a continuous contacting surface of substantially tubular form. Likewise mounted upon this head, diametrically opposite, and insulated therefrom at 26 is a similar post comprising the contacts 27 and 28 insulated one from another at 29, the length of the insulating member 29 being less than the effective length of the corresponding contact 19; it being understood that these contact posts are embraced by the switch member shown in Fig. 3.

The dynamo is preferably a four-pole machine having two sets of brushes 30 and 31

positioned at the neutral points and electrically connected in pairs, as shown in Fig. 2 of the drawings. Brushes 31 are in electrical connection by suitable conductors 5 with the contact member 28 and an auxiliary brush 32 is connected through a series resistance 33 with the contact member 27.

It may here be noted that as the dynamo armature slides, as above described, due to 10 the pulling of the field magnets, the switch members 19 which normally bridge the contacts 25 and 27 are moved steadily toward the right in Fig. 1 of the drawings until they first connect contact 25 with contacts 15 27 and 28 and thereafter, upon further movement, connect contact 25 with contact 28 only.

Referring now for the electrical connections to Fig. 2 of the drawings, there is indicated at 34 a storage battery, the circuit of which leads first through a spring-retracted switch 35 which may be controlled by a foot pedal of an automobile. From this point the circuit leads to the contact 25 and continues through contact 27 and resistance 33 to the auxiliary brush 32. Passing through the armature from this displaced brush, the current traverses brushes 30, the series field 36 of the motor, and returns to 30 the battery. The winding 37 of the electromagnet on the dynamo head is bridged across the battery, as shown.

The action of the above apparatus may be outlined as follows:

Upon switch 35 being closed the current passes through the above circuit to brush 32 and returns to the battery through brushes 30 and field 36. The displaced position of brush 32 results in a marked 35 efficiency of action of the armature windings due to causes outlined in my co-pending application above referred to. This action, in conjunction with the effect of resistance 33, results in a feeble torque or turning moment 40 of the armature as the latter is drawn into registry with the field magnets and the gears 5 and 3 into mesh. During this movement, however, the upper contact 19 when it reaches contact 28 leads current to brushes 45 31 and 32 in parallel and upon leaving contact 27 it leads current to brushes 31 only which, being properly positioned, give the dynamo its full torque for starting the engine 2. Upon the engine being started and 50 speeding up with an attendant increase in counter-electromotive force of the dynamo, the pull of the field magnets is weakened and spring 9 throws the gears out of mesh. If switch 35 has meanwhile been opened, the 55 collar 14 follows the armature returning the switch member 18 to normal position. If, however, switch 35 is held closed, the magnet 15 prevents the return of collar 14 until the circuit through the magnet is 60 broken. It is to be particularly noted that 65

due to the length of the contact member 19 there is no breakage of the circuit through the motor armature throughout the above action, and thus an interrupted torque as well as the chance of burning the contacts 70 is avoided. It is also to be noted that the frequent sliding movements of the switch contacts tend to maintain them in a condition of high electrical efficiency.

It will thus be seen that there is provided 75 simple apparatus for attaining the objects of this invention.

As many changes might be made in the above construction, and as many apparently different embodiments might be made of 80 this invention without departing from the scope thereof, it is intended that all features herein described or shown in the accompanying drawings shall be interpreted as illustrative and not in a limiting sense.

Having thus revealed this invention, I claim as new and desire to secure the following combinations of elements, or equivalents thereof, by Letters Patent of the United States:

1. In apparatus of the class described, in combination, an electric motor provided with a brush upon the neutral point of its commutator, a brush circumferentially offset from its neutral points, a pair of contacts respectively connected with said brushes, a source of current, a member connected with said source of current, a contact member adapted to make sliding contact with said first contacts and move from 100 one to the other thereof, said contact member being electrically connected with said first member, and means adapted to move said contact member as the motor is started.

2. In apparatus of the class described, in 105 combination, an electric motor provided with a brush upon the neutral point of its commutator, a brush circumferentially offset from its neutral points, a pair of contacts respectively connected with said 110 brushes, a source of current, a member connected with said source of current, a contact member adapted to make sliding contact with said first contacts and move from one to the other thereof, said contact member being electrically connected with said first member, and means adapted to move said contact member as the motor is started, said contact member being shaped to connect the two first contacts one with another 115 during its movement from one to the other thereof.

3. In apparatus of the class described, in combination, an internal combustion engine, a dynamo provided with an endwise slideable armature normally out of registry with its field magnets, gearing positioned between said engine and said dynamo adapted to form a power transmitting connection therebetween as said armature slides, a 125 130

- brush upon the commutator of said dynamo substantially at a neutral point, a brush upon said commutator angularly offset from its neutral points, a source of current, a 5 contact connected with said second brush, a contact connected with said first brush, a slideable contact member connected with said source of current and normally engaging said first contact, and means adapted as said 10 armature slides to move said slideable member into engagement with said second contact.
4. In apparatus of the class described, in combination, an internal combustion engine, 15 a dynamo provided with an endwise slideable armature normally out of registry with its field magnets, gearing positioned between said engine and said dynamo adapted to form a power transmitting connection there- 20 between as said armature slides, a brush
- upon said commutator angularly offset from its neutral points, a source of current, a stationary member adapted to be connected with said source of current, a second stationary contact member having contacts respectively connected with said second and said first brushes, a sliding bridge connecting said contact members and normally resting against the contact leading to said offset brush, and a device adapted to slide said bridge into electrical connection with said first brush as the armature slides into registry with the field magnets of the motor.
- In witness whereof, I hereunto subscribe my name, as attested by the two subscribing witnesses.

JOSEPH BIJUR.
